(57) **CLAIM**

We claim the ornamental design for an umbrella-type clothes drying line with removable cover, as shown and described.

DESCRIPTION

FIG. 1 is a perspective view of an umbrella-type clothes drying line with removable cover showing our new design with a flap thereof bending outwards;

FIG. 2 is a front elevational view thereof showing the flap bending outwards;

FIG. 3 is a bottom plan view thereof showing the flap bending outwards and diagonal lines representing cover supports, the outline of which are shown in FIG. 1; the broken lines depict environmental structure for illustrative purposes only and form no part of the claimed design;

FIG. 4 is a top plan view thereof showing the flap bending outwards;

FIG. 5 is a rear elevational view thereof; and,

FIG. 6 is a front elevational view showing the umbrella-type clothes drying line with removable cover in use with the flap bending outwards; the broken lines depict environmental structure for illustrative purposes only and form no part of the claimed design.
